[57] CLAIM

The ornamental design for a hand held digital communicator housing, as shown and described.

DESCRIPTION

FIG. 1 is a top, front and left side perspective view of a hand held digital communicator housing showing our new design;

FIG. 2 is a top plan view thereof;

FIG. 3 is a bottom plan view thereof;

FIG. 4 is a right side elevational view thereof, the left side being a mirror image;

FIG. 5 is a rear elevational view thereof; and

FIG. 6 is a front elevational view thereof.
